United States Patent Office

Des. 205,404
Patented August 2, 1966

205,404

SPRAYING UNIT

Dale E. Wolford, Ashland, Ohio, assignor to The F. E. Myers & Bro. Co., Ashland, Ohio, a corporation of Ohio

Filed Aug. 24, 1965, Ser. No. 86,690

Term of patent 14 years

(Cl. D31—3)

FIG-1

FIG-2

FIG-3

FIGURE 1 is a perspective view of a spraying unit embodying my new design.

FIGURE 2 is a perspective view thereof looking in from the right side of FIGURE 1.

FIGURE 3 is a perspective view thereof looking in from the left side of FIGURE 1; and

FIGURE 4 is a plan view of the spraying unit.

I claim:

The ornamental design for a spraying unit, substantially as shown.
